UNITED STATES PATENT OFFICE.

ARTHUR A. BERNDT, OF CHICAGO, ILLINOIS, ASSIGNOR TO KURZ BROS. CO., OF CHICAGO, ILLINOIS, A CORPORATION OF ILLINOIS.

BOTTLE CRATE.

Application filed April 5, 1924. Serial No. 704,316.

To all who it may concern:

Be it known that I, ARTHUR A. BERNDT, a citizen of the United States, residing at Chicago, in the county of Cook and State 5 of Illinois, have invented certain new and useful Improvements in Bottle Crates, of which the following is a specification.

This invention relates to bottle-carrying crates, and more especially crates of the 10 multiple cell type designed to hold the bottles in spaced relation. Among the objects of the invention are, to provide an improved structure of bottle separating and spacing strips adapted to accommodate the 15 variations in external diameter of the bottles which frequently are found in bottles of like capacity, to provide improved means for fastening the ends of the spacing and separating strips in the side and end walls of the 20 crate so as to secure the strips not only against pulling out but against yielding at their ends with consequent bowing or bending, to provide an improved base or bottom structure, and more especially improved 25 means for securing said structure strongly and rigidly to the side and end walls, to provide simplified and improved means for strongly uniting the several wall sections of the 30 crate, to provide improved means for strongly and rigidly uniting the side and end walls at the corners of the crate, and to provide a bottle crate of strong and rigid construction capable of being quickly assembled 35 during manufacture and well adapted to withstand rough handling and usage without impairment.

Other objects and attendant advantages of the invention will be apparent to persons skilled in the art as the same becomes better 40 understood by reference to the following detailed description, taken in connection with the accompanying drawings in which I have illustrated one practical and efficient embodiment of the principle of the invention, and wherein—

Fig. 1 is a sectional plan view taken on the line 1—1 of Fig. 3 in the plane of the upper group of spacing strips;

Fig. 2 is a sectional plan taken on the line 50 2—2 of Fig. 3, in the plane of the bottom or base member;

Fig. 3 is a vertical transverse section taken on the line 3—3 of Fig. 1;

Fig. 4 is an enlarged horizontal section

through one corner of the crate illustrating the corner joint and fastening means;

Fig. 5 is an enlarged vertical section on the line 5—5 of Fig. 1, illustrating the means for anchoring the ends of the spacing strips;

Fig. 6 is an enlarged vertical section on the line 6—6 of Fig. 2, illustrating the means for anchoring the bottom or base member and attaching the shoe frame;

Fig. 7 is a view similar to Fig. 6, taken on the line 7—7 of Fig. 2;

Fig. 8 is a fragmentary plan view enlarged of one end of a wire loop and its attachment clip;

Fig. 9 is a fragmentary side elevation of the crate showing the countersinking of the 70 partition strips and base attachment clips; and

Fig. 10 is a cross-section on line 10—10 of Fig. 5.

A crate constructed in accordance with my 75 present invention consists of a rectangular box-like structure having side and end walls, a reticulated metal bottom or base, one or more groups of transverse bottle-separating and spacing strips, and a shoe frame or sole 80 attached to the lower edge of the box body below the plane of the bottle-supporting bottom member. In the drawings 10, 11 and 12 designate upper, intermediate and lower 85 sections of the side walls of the crate, and 13, 14 and 15 designate corresponding sections of the end walls. 16 designates the end members and 17 the side members of a low rectangular shoe frame or sole that constitutes the bottom frame member of the complete 90 crate.

The bottom or bottle-supporting wall of the crate preferably takes the form and structure illustrated in Fig. 2; although it should be understood that, so far as certain 95 other improved structural features of the crate hereinafter described are concerned, any suitable form and structure of bottom may be employed. The structure herein shown includes a group of parallel wire loops preferably disposed crosswise, or between the longitudinal sides, of the crate body or shell as shown, and each comprising parallel longitudinal limbs 18, an integral connecting limb 19 at one end, and a pair of endwise abutting half limbs 20 at the other end. 21 designates as an entirety each of a plurality of connecting and spacing strips for the wire 100 105

loops, each of which is cut and pressed to shape from a single flat strip of sheet metal. In the formation of the strips 21, said strips are longitudinally slitted at uniform intervals lengthwise thereof on lines indicated at 22, and the portions between and outside of the slits 22 are offset on opposite sides of the plane of the strip, and between said offset portions the wire loops are inserted endwise. The assembled structure is then placed in a suitable press, by which the offset portions between the longitudinal limbs of each loop are pressed back into a common plane, thereby securely gripping and rigidly spacing the longitudinal limbs of the loops. The portions of the strips between adjacent wire loops are transversely arched as shown at 23 to afford increased stiffness.

The specific structure of the bottom member last described is not claimed herein, since the same forms the subject-matter of a companion application filed by me concurrently herewith, Serial No. 704,317.

The flat ends of the strips 21 are apertured, as shown at 24 in Fig. 7, and in the formation of the aperture the metal is not excised, but is displaced upwardly forming a tang 25 which enters a kerf 26 previously prepared in the lower edge of the crate section 15. The loop members of the bottom are secured in the side walls of the crate by means of sheet metal clips that are folded and slipped over the transverse members 19 and 20 of the loops and are then pressed together, thereby forming a sleeve or ferrule 27 (Fig. 6) encircling the members 19 and 20 and a pair of contiguous leaves or wings 28 and 29, which are apertured in the same manner as the ends of the spacing strips 21 prior to folding, thereby forming upwardly and downwardly projecting tangs 30 and 31 which enter previously formed kerfs 32 and 33 in the frame sections 12 and 16, respectively. By reference to the detail view Fig. 8 it will be seen that the ends of the ferrule 27 are mitered at 27' so as to encircle the elbow bends at the end of the wire loop, and the wings or leaves 28 and 29 are pressed together around the outer sides of the elbows, as shown at 28', so that the ferrule also serves to securely bond together the meeting end sections 20 of the wire embraced by the ferrule and prevent them from spreading apart. The shoe frame is attached to the bottom of the lower crate wall section by nails 34 driven from beneath through the members 17 of the shoe frame, the apertures of the spacing strips 21 and into the lower sections 15 of the crate wall, as clearly shown in Fig. 7, and by nails 35 similarly driven through the shoe sections 16, the apertures of the loop-fastening clips and into the members 12 of the lower section of the crate wall, as clearly shown in Fig. 6. By reason of this construction, the tangs 25 and 30, 31

not only facilitate the accurate positioning of the bottom member on the lower section of the crate wall before the shoe frame is applied, but the tangs 30, 31 also serve to center or position the shoe frame before the same is nailed, and the tangs, by direct or indirect abutment against the nails, afford a much stronger resistance to pulling out strains than would be afforded by the thin metal of the strips and clips alone. In other words, the ends of the intersecting members of the bottom are anchored in the walls with increased strength and security.

At spaced intervals above the bottom the crate is equipped with a plurality of spaced groups of cell-forming, or bottle-separating and spacing strips designated as an entirety by 36. These are thin flat sheet metal strips, the sides of which are bent downwardly or arched at uniform intervals lengthwise thereof, as shown at 37, so as to provide yielding or elastic bearings of the edges of the strips against the circular wall of the bottle. This feature of the strip, however, is not new with me, being disclosed in Letters Patent to Foreman No. 1,368,221, February 8, 1921; but I have improved the said strip in the direction of increasing its stiffness in a vertical plane by forming therein longitudinal ribs 38 which extend midway between the downwardly bent or arched portions 37. The strips are preferably arranged in alternate overlapping and underlapping relation, after the fashion of ordinary weaving, in the manner also shown in the Foreman patent above-identified. The ends of the spacing and separating strips 36 are secured to and between the sections of the crate body in the manner and by the means shown and described in connection with the bottom strips 21. That is to say, a depending tang 39 is struck downwardly, thereby forming a hole 41 (Fig. 5), through which a nail 42 is driven. The tangs 39, which are preferably curved in cross-section, as shown in Fig. 10, to afford greater resistance to bending, are driven into the wood and reinforce and strengthen the anchorage of the strip in the same manner as the tangs 26 and 30 and 31 already described.

The side wall sections 10, 11 and 12 and end wall sections 13, 14 and 15 are rigidly and strongly united at their meeting edges by means of dowel pins or posts 43 in the manner clearly shown in Fig. 3; two or more such dowels being preferably used on each side.

The corners of the crates are reinforced and strengthened by means of thin sheet metal angle strips 44 inserted between the meeting ends of the side and end walls in the manner clearly shown in Fig. 1. The use of such angle strips at the corners of the box is not new with me, but I have devised an improved and stronger fastening for the

corners, which is shown in detail in Fig. 4 and comprises a nail 45 that is driven obliquely through the meeting ends of the end and side walls and pierces the angle strip 44. Heretofore it has been the custom to drive the nails which unite the walls at the corners in a direction parallel with one wall and normal to the other. Where this is done, the separating or parting strain is manifestly either transverse to the nail or parallel with it, and where parallel with the nail the holding power of the latter is very light. By driving the nails obliquely in the manner shown in Fig. 4, the outward tendency of either the side or the end wall is in a direction oblique to the nail, and hence the latter secures both walls against separation with substantially equal tenacity.

In order to provide snug joints at the meeting edges of the several wall sections and of the lower wall section and shoe frame, the upper edges of the intermediate and lower wall sections and the lower edge of the lower wall section are countersunk, as shown in Fig. 9, to seat the ends of the spacing strips 36 and 21 and the wings 28 and 29 of the attachment clips; the countersink in each case being the thickness of the metal occupying the same.

The end wall sections 13 are equipped with the usual hand holes 46 (Fig. 3).

The described construction provides a very strong, durable and yet light bottle crate capable of withstanding hard knocks and rough usage with minimum liability of deformation or breakage. The described manner and means of anchoring the bottom and spacing strips in and between the wall sections is well adapted to maintain said strips always in a taut condition, free from bending, bowing or other deformation. It may also be noted with reference to spacing and separating strips that they have a limited amount of play at their intersections, between the proximate ends of the ribs 38, whereby the bottle cells formed thereby can accommodate considerable variations in the diameters of bottles, independently of the yielding character of the arched portions 37 of the strips which lie against the bottles.

While I have herein shown and described an embodiment of the invention which has been found to satisfactorily effectuate the stated purposes and objects thereof, it is manifest that the specific structural details may be varied without altering the essential character of the invention. Hence, I reserve such variations and modifications as fall within the spirit and purview of the appended claims.

I claim—

1. A bottle crate, comprising walls, a shoe frame attached to the lower edges of said walls, a bottle-supporting base including a

series of parallel rectangular narrow wire loops, and attachment clips for said base embracing the end members of said loops and formed with a pair of folded flat wings lying in the joint at the meeting edges of said walls and shoe frame, said wings being formed with integral oppositely extending tangs entering kerfs in said meeting edges. 70

2. A bottle crate, comprising walls, a shoe frame applied to the lower edges of said walls, a bottle-supporting base including a series of parallel rectangular narrow wire loops, attachment clips for said base embracing the end members of said loops and formed with a pair of folded flat wings lying in the joint at the meeting edges of said walls and shoe frame, said wings having registering holes and integral oppositely extending tangs at the outer sides of said holes entering kerfs in said meeting edges, and nails driven through said shoe frame and holes into the lower edges of opposed walls of the crate. 80

3. A bottle crate, comprising side and end walls, a shoe frame attached to the lower edges of said walls, a bottle-supporting base comprising a series of parallel rectangular narrow wire loops and spacing strips transversely intersecting said loops, the ends of said spacing strips lying in the joints at the meeting edges of one opposed pair of said walls and shoe frame and formed with integral tangs entering kerfs in one of said edges, and attachment clips embracing the end members of said loops and formed with a pair of folded flat wings lying in the joint at the meeting edges of the other opposed pair of said walls and shoe frame, said wings being formed with integral oppositely extending tangs entering kerfs in said meeting edges. 90

4. A bottle crate, comprising side and end walls, a shoe frame applied to the lower edges of said walls, a bottle-supporting base comprising a series of parallel rectangular narrow wire loops and spacing strips transversely intersecting and gripping said loops, the ends of said spacing strips lying in the joints at the meeting edges of said end walls and shoe frame and formed with integral tangs entering kerfs in one of said edges, attachment clips embracing the end members of said loops and formed with a pair of folded flat wings lying in the joint at the meeting edges of said side walls and shoe frame, said wings having registering holes and integral oppositely extending tangs at the outer sides of said holes entering kerfs in said meeting edges, and nails driven through said shoe frame and holes into the lower edges of said side walls. 105

5. A crate bottom, comprising a plurality of relatively long narrow rectangular wire loops, metal strips rigidly connecting and spacing said loops, and attachment clips em- 110

bracing the transverse end members of said loops and adapted for attachment to the walls of the crate.

6. A crate bottom, comprising a plurality of relatively long narrow rectangular wire loops, metal strips rigidly connecting and spacing said loops, and attachment clips comprising ferrules embracing the transverse end members of said loops and flat folded wings integral with said ferrules adapted to enter joints in the crate walls and apertured for the passage of nails therethrough.

7. A crate bottom, comprising a plurality of relatively long narrow rectangular wire loops, metal strips rigidly connecting and spacing said loops, and attachment clips comprising ferrules embracing the transverse end members of said loops and flat folded wings integral with said ferrules adapted to enter joints in the crate walls and provided respectively with oppositely extended tangs.

8. A crate bottom, comprising a plurality of relatively long narrow rectangular wire loops, metal strips rigidly connecting and spacing said loops, said strips having flat ends adapted to enter joints in the walls of the crate and apertured for the passage of nails and formed with integral tangs, and attachment clips comprising ferrules embracing the transverse end members of said loops and flat folded wings integral with said ferrules adapted to enter joints in the crate walls and provided with registering nail holes and oppositely extended tangs.

9. A crate bottom, comprising a plurality of relatively long narrow rectangular wire loops, means connecting and spacing said loops, and attachment clips comprising ferrules embracing the transverse end members of said loops and flat folded wings integral with said ferrules adapted to enter joints

in the crate walls and provided with registering nail holes, the ends of said ferrules being mitered to embrace the corner portions of said loops, and said wings being pressed together around the outer sides of said corner portions.

10. A partition strip for bottle crates and the like, consisting of a thin metal strip formed at spaced intervals lengthwise thereof with downwardly bent concave bottle-engaging flanges and with longitudinal stiffening ribs between said flanges.

11. A partition strip for bottle crates and the like, consisting of a thin metal strip formed at spaced intervals lengthwise thereof with downwardly bent concave bottle-engaging flanges and with upwardly struck longitudinally stiffening ribs midway between said flanges.

12. A metal partition strip for bottle crates and the like, consisting of a metal strip having flat end portions adapted to enter joints in opposed walls of the crate, said end portions being formed with integral tangs adapted to be driven into one of said walls.

13. A metal partition strip for bottle crates and the like, consisting of a metal strip having flat end portions adapted to enter joints in opposed walls of the crate, said end portions being formed with integral transversely curved tangs adapted to be driven into one of said walls.

14. A metal partition strip for bottle crates and the like, consisting of a metal strip having flat end portions adapted to enter joints in opposed walls of the crate, said end portions being formed with nail holes and with integral tangs located outwardly of said nail holes adapted to be driven into one of said walls.

ARTHUR A. BERNDT,
